UNITED STATES PATENT OFFICE.

FRED KING, OF CARMARTHEN, WALES.

ADJUSTABLE RUBBER PAD, FERRULE, OR TIP FOR WALKING-STICKS, CRUTCHES, &c.

1,372,517.

Specification of Letters Patent.

Patented Mar. 22, 1921.

Application filed April 10, 1920. Serial No. 372,784.

To all whom it may concern:

Be it known that I, FRED KING, a subject of the King of England, residing at Carmarthen, in Wales, Great Britain, have invented certain new and useful Improvements in Adjustable Rubber Pads, Ferrules, or Tips for Walking-Sticks, Crutches, and such like, of which the following is a specification.

10 This invention relates to a ferrule or tip for walking-sticks, crutches and such like, in which ferrule there is an elastic pad. Sticks and the like when they have been heretofore made with elastic pads at the tips 15 have had the pad, usually of rubber, with the rubber in the form of rubber caps for the stick-end, or have had a piece of rubber inserted in and projecting from an ordinary ferrule (or from a ferrule split at its end 20 into claws engaging a groove in the piece of rubber) and not adjustable endwise to compensate for wear. The object of the present invention is to provide the combination 25 of a ferrule with means to retain an elastic pad in it so that it projects beyond the end of the ferrule and can be adjusted as it wears, and removed and replaced by a fresh pad as may be desired. This is of practical value in that the ferrule itself will 30 last as long as the stick lasts, and only the elastic pad need ever be renewed.

Accordingly, the present invention comprises the combination of a ferrule shaped at one end to engage the stick or other article to which it is to be fitted, and divided at its other end into spring-fingers which are screw-threaded or otherwise provided with projections on their inner faces, and a removable sleeve which encircles and is engaged by bayonet-joint slots and studs with the ferrule, and has a bore reduced so that by forcing the sleeve over the exterior of the spring-fingers they can be pressed inward toward an elastic pad (say 40 a piece of rubber) in between the fingers so as to grip it. The elastic pad protrudes beyond the end of the ferrule and beyond the ends of the fingers, and as it wears away it can be re-adjusted so as always to present 45 a projecting end until it is too short to be employed any longer, when after slackening back the sleeve it can be removed and replaced by a fresh pad.

In the accompanying drawings which

illustrate one construction of a combination 55 according to the present invention,

Figure 1 is an elevation of the complete combination with the parts in the relative positions they assume when the whole is in place upon the stick or the like.

Figs. 2, 3 and 4 are vertical central sections of the three elements which compose the combination illustrated in Fig. 1, and

Fig. 5 is a plan view of a sleeve which in Fig. 4 is seen in section.

With reference to these drawings, the ferrule 1 is shaped at its upper end 2 to engage the article to which it is to be fitted, and it is provided with holes 3 into which nails may be driven to secure it to the tip 70 of the article. At the lower end the ferrule is divided by vertical open-ended slots 4 and 5 into spring-fingers 6 on the inner faces of which a screw-thread 7 is provided. This thread is a buttress thread with its flats 75 directed toward the tips of the fingers. A removable sleeve 8 encircles the ferrule and is engaged by studs 9 fixed in said sleeve with the ferrule by way of the bayonet-joint slots 10. The bore of the sleeve 8 is 80 tapered internally, as shown, and at its lower end 11 is reduced in diameter to a degree which makes the internal diameter of the bore there less than the external diameter of the lower part of the ferrule.

The rubber pad 12 is to be inserted into the lower end of the ferrule 1 between the spring-fingers 6. If thereafter the sleeve is forced up over the outside of the spring-fingers 6 it will force them inward so as to 90 grip the pad 12 and keep it in place, and by giving the sleeve a partial turn about its own axis the studs 9 which project from its interior are made to engage the short right-angled bayonet-joint slots 10 so as to hold 95 the sleeve in place upon the ferrule and keep it in a position in which the spring-fingers grip the pad 12 so that the latter cannot escape.

When the parts are thus engaged they 100 assume the relative positions in which they are shown in Fig. 1, from which it will be seen that the lower end of the pad 12 protrudes beyond the lower ends of the sleeve 8 which is below the lower ends of the fingers 6 within the sleeve. The screw-threads 7 facilitate the forcing of the rubber pad into the lower end of the ferrule and also

serve as projections which prevent it from coming out again accidentally. The flats of the threads prevent undue compression of the rubber under load.

5. When the sleeve is home in place, as in Fig. 1, its outer surface would preferably be flush, as shown, with the outer surface of the ferrule 1.

What I claim as my invention and desire to secure by Letters Patent is: —

1. As an article of manufacture, a ferrule having means for attaching it to the article to be fitted therewith, spring fingers formed on said ferrule for the reception of a pad, and means coöperating with said fingers for forcing them into engagement with the pad, substantially as described.

2. As an article of manufacture, a ferrule having means for attaching it to the article to be fitted therewith, spring fingers formed on said ferrule and adapted to adjustably receive a pad, and means coöperating with said fingers for forcing them into engagement with said pad, substantially as described.

3. As an article of manufacture, a ferrule having means for attaching it to the article to be fitted therewith, spring fingers formed on said ferrule, projections on said fingers for engagement with a pad, and means coöperating with said fingers to force said projections into engagement with said pad, substantially as described.

4. As an article of manufacture, a ferrule having means for attaching it to the article to be fitted therewith, fingers formed on said ferrule, buttress threads on said fingers having their flats directed toward the

tips of the fingers, and means for forcing said threads into engagement with a pad, substantially as described.

5. As an article of manufacture, a ferrule having means for attaching it to the article to be fitted therewith, fingers formed on said ferrule, means on said fingers adapted to adjustably coöperate with a pad, a sleeve for forcing said last mentioned means into engagement with said pad, and means for securing the sleeve in coöperative position with said fingers, substantially as described.

6. As an article of manufacture, a ferrule having means for attaching it to the article to be fitted therewith, fingers formed on said ferrule, means on said fingers adapted to adjustably coöperate with a pad, a sleeve for forcing said last mentioned means into engagement with said pad, and a bayonet joint for holding said sleeve in coöperation with said fingers, substantially as described.

7. The combination with a ferrule shaped at one end to engage the article to which it is to be fitted and divided at its other end into spring-fingers having buttress threads with their flats directed toward the tips of the fingers, of a removable sleeve which encircles and is engaged by bayonet-joint slots and studs with the ferrule and has a bore reduced for the purpose described, and an elastic pad protruding beyond the ends of the fingers, substantially as described.

In testimony whereof I affix my signature.

FRED KING.
